CLAIM

The ornamental design for an electronic printer, as
shown.

DESCRIPTION

FIG. 1 is a top plan view of an electronic printer in
accordance with my new design;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a bottom plan view thereof;

FIG. 7 is a front perspective view thereof; and

FIG. 8 is a view similar to FIG. 7 showing the separator
in a cut sheet guide mode.

FIG. 1

FIG. 2

FIG. 3

FIG. 4

FIG. 5

FIG. 6

FIG. 7

FIG. 8
